UNITED STATES PATENT OFFICE

ROBERT A. BALDERSON, OF PITTSBURGH, PENNSYLVANIA, ASSIGNOR TO ARMSTRONG CORK COMPANY, OF PITTSBURGH, PENNSYLVANIA, A CORPORATION OF PENNSYLVANIA

METHOD AND MACHINE FOR PRINTING FLOOR COVERINGS

Application filed July 11, 1928. Serial No. 291,818.

This invention relates to the art of printing, and more particularly to block printing machines used in the decorating of printed floor coverings, such as linoleum and felt base goods. More particularly, the invention relates to the application of paint or color to the printing surfaces of the printing blocks.

In the operation of the ordinary block printing machine, a color carriage passes under a printing block to apply color to the printing surface of the block prior to each operation of the printing block. The color carriage is designed to travel from one side of the head to the other on one printing cycle, and to move back on the next printing cycle.

As heretofore constructed, such carriages have generally had a single trough adapted to hold paint and have a single roll adapted to apply paint to the printing surface of the block. This arrangement permits of the application of only one color to the printing surface of the block. It has been proposed to divide the trough transversely of its length so that different portions of the roll will apply different colors of paint to different areas of the printing block crosswise of the block.

In a co-pending application of Charles F. Humphreys, filed July 23, 1928, Serial No. 294,743, there is disclosed a block printing machine wherein the color carriage is divided longitudinally to provide parallel paint troughs along the carriage. In the construction shown in the said Humphreys' application, the arrangement is such that the rolls in the parallel troughs can be tilted to render one or the other effective for applying paint to the printing surface, but the arrangement does not permit of the use of both rolls at the same time. This arrangement, while increasing the number of colors which may be printed by a single head, requires that the printing head be divided longitudinally into relatively movable sections so that the sections which are intended for the printing of one color will not receive paint when the roller for applying the other color passes under the printing head.

According to the present invention, the arrangement is such that the paint carriage is divided longitudinally into two or more

parallel compartments. A paint applying roll is provided for each compartment and the arrangement is such that all of the rolls may operate simultaneously in applying paint to the printing block. In order, however, that two colors will not be applied to the same portion of a single printing block, the rolls and the block are maintained in contact during only a portion of the travel of the carriage under the block. One roll will therefore apply color to one part of the block and the other roll to another part of the block; but the rolls will contact with the block during only a portion of the travel of the carriage so that there will be no overlapping of two colors on a single portion of the block.

In the accompanying drawings I have illustrated certain embodiments of my invention, but it will be understood that these are merely illustrative and that the invention is not restricted to the particular constructions shown.

In the drawings—

Figure 1 is a side elevation of a portion of a block printing machine showing only so much of said machine as relates to the present invention, the mechanism for operating the printing heads being omitted, the drawing being more or less diagrammatic;

Figure 2 is a top plan view of the track and rollers for one end of the color carriage;

Figure 3 is a top plan view of a color carriage divided both longitudinally and transversely by means of which eight different color compartments are provided;

Figure 4 is an end view of the longitudinally divided color carriage;

Figure 5 is a transverse section through the carriage;

Figure 6 is a bottom plan view of the printing surface of a printing block for cooperation with the divided paint carriage, the view being more or less diagrammatic;

Figure 7 shows a slightly modified arrangement, the view being an end elevation of the carriage; and

Figure 8 is a longitudinal vertical section in the plane of line VIII—VIII of Figure 7.

In the construction shown in Figures 1 to 5, inclusive, 2 represents the frame of the

machine having a bed 3 over which the material to be printed upon is intermittently moved lengthwise of the bed. Printing heads or printing blocks are indicated at 4 and 5. The printing blocks 4 and 5 have the printing area thereof divided longitudinally of the head, that is transversely to the direction of travel of the material, into two or more separate printing surfaces 4^a and 4^b and 5^a and 5^b, respectively. In Figure 1 I have merely shown that carriage which is intended for cooperation with the printing head 5. A similar carriage could be provided for the head 4 and for any other head on the machine wherein the printing surfaces are divided for cooperation with a divided carriage.

In the drawings, the color carriage is designated generally by the reference numeral 6. This carriage comprises a trough 7 adapted to span the bed of the machine and which is divided longitudinally by means of a central partition 8 into separate compartments 9 and 10. In each of the compartments 9 and 10 is a paint spreading roller 11. The rollers 11 are supported on shafts 12 which pass through bearings in the end walls of the trough. Either or both ends of the shaft 12 are provided with gear wheels 13 meshing with other gear wheels 14. Extending along the length of the bed of the machine is a rack 15 and a track 16. The gear wheels 14 engage in the rack 15 to rotate the gear wheels 13 and thereby rotate the rollers 11. The arrangement is such that the rollers will have a peripheral speed of movement of the carriage so that in passing under the printing surface of the block 5 they will roll against the block and not merely wipe the under faces thereof. This is the usual practice in machines of this kind. The carriage itself is supported on rollers 17 adapted to travel on the track 16.

These rollers have gear portions 17' adapted to engage in the rack 15 for positively rotating the rollers whereby it is assured that they will roll and not slide along the track 16. This is also quite common in printing machines of this type. As heretofore constructed, the track 16 has been in the form of an ordinary rail, and the rollers 17 have been of uniform diameter. According to the present invention the rollers 17 at one side of the carriage have an inner portion 17^a of reduced diameter and another portion 17^b of ordinary diameter. The other roller 17 at the other side of the carriage has the reduced portion 17^a reversed, the portion 17^b being next the flange. The track 16 has cam surfaces 16^a and 16^b thereon which are raised above the normal level of the track. The cam surfaces 16^a are located on the side of the rail immediately next the rack 15 and the cam surfaces 16^b are located along the other side of the rail 16.

Assuming in Figures 1 and 2 that the car-

riage starts to move from right to left, it will roll along the track 16. The reduced portion 17^a of the left hand roller will ride over the cam surface 16^b, the portion 17^b of this roller supporting the load. When the carriage has moved under the block 5 to the point where the left hand inking roller 11 has just reached the center of the block 5, the portion 17^b of large diameter of the left hand roller will ride up on to the raised surface of 16^a. At the same time the portion 17^b of the right hand roller will ride up on the raised portion 16^b. The entire carriage will thus be raised vertically a very slight distance. This distance will be sufficient to bring the left hand roller to a position where it will apply ink to the surface 5^b while the right hand roller inks the surface 5^a. Thus each roller will apply ink to only one of the two surfaces.

When the left hand roller 11 has passed across the surface 5^b, the rollers 17 will ride off the cams 16^a and 16^b, to lower the carriage, so that the right hand roller 11 will not apply ink to the surface 5^b. Thus there will be no overlapping of two colors on the same printing surface, but different colors will be applied to different longitudinal divisions of the printing surface at the same time.

While I have shown the head as being divided along its center line, the line of division may occur at any suitable point, this being determined by the location of the cams 16^a and 16^b.

When the carriage reaches the limit of its movement, and the carriage is entirely clear of the head, the head comes down to print. After the head has been lifted and raised to color receiving position, the carriage starts moving to the right. It will not be lifted until the right hand roller 17 engages the cam 16^b at which time the right hand inking roll 11 will be at the line of division between the two printing sections of the block and the left hand roller 11 will be just about to move under the block. Thus the same colors will be applied to the same areas on the reverse movement of the carriage.

By reference to Figure 6 it will be seen how the printing surfaces 5^a and 5^b are disposed. These printing surfaces might be small individual patterns or large solid colors.

In addition to dividing the trough longitudinally, it may also be divided transversely, as indicated in Figure 3, wherein 20 designates the carriage having a longitudinal partition 21 and transverse partitions 22. There may be any suitable number of transverse partitions. In the arrangement shown in Figure 3, the color box is divided up into eight separate compartments. By dividing the head both transversely and longitudinally, a wide variety of colors can be used in a given pattern without increasing the

number of printing heads and the pattern can be more intricate. Using a printing block as shown in Figure 6 with a trough divided both ways, each of the several patterns shown might be in a different color, and they could all be printed at one time, or on one stroke of the printing head.

It will thus be seen that the invention not only provides a new improvement in printing machines, but introduces a new method in the art of rug printing. It permits of the simultaneous application of different colors across different portions of a rug design at a given printing station.

In Figures 7 and 8 I have shown a slight modification for securing the same results and by means of which only the rollers are raised while the trough itself remains in the same horizontal plane. In this construction, 25 designates the bed of the machine and 26 is the color box having a longitudinal partition 27 separating the trough into two compartments 28 and 29. In each compartment is a paint applying roller 30 having a shaft 31 passing through a vertical slot 32 in the end wall 33 at each end of the trough. Inasmuch as the effective vertical movement of the rolls into and out of operative position need be only approximately 3/32 of an inch, the slots 32 are very short. The carriage is supported on the rollers 34 that roll on a rail 34' extending along the bed of the machine at each side thereof.

At each end of the trough is a vertically reciprocable frame 35 through which the shafts 31 pass. This frame 35 has inwardly turned bridge portions 36 from which depend extensions 37 that carry packings for closing the slots 32. The extension 37 also provide bearings for the rollers and supports for doctor blades which cooperate with the rollers. At the center of each frame 35 is a depending arm 38 having a roller 39 at the bottom thereof. The rollers 39 are adapted to engage cams 40 which are parallel to the rails 34 and spaced inwardly from these rails. The cams are so located with respect to the printing head that the frames 35 will be lifted when the carriage is at a predetermined location under the printing head 41. The printing head 41 has longitudinally separate printing surfaces 42 and 43.

In Figure 8 I have shown compression springs housed in the ends 33 for pressing upwardly on the shafts 32. These springs serve to assure both rollers applying paint uniformly to the respective printing surfaces 42 and 43, these springs not being sufficient to hold the frames up when the rollers 39 are off the cams 40.

In Figure 8 of the drawing I have shown a bearing strip 45 at each end of the printing block which projects slightly below the printing surface of the block. The roller

30 is adapted to contact with this bearing strip 45. By reason of this arrangement the position of the roll with respect to the printing surface can be accurately maintained, it being desirable that the roll shall not actually touch the printing surface, but shall travel a few thousandths of an inch below the plane of the printing surface.

It will be understood that in addition to the particular structures herein shown for effecting a relative movement of the carriage and printing block at a time when the carriage is passing under the block, other means may be employed. For instance, it is contemplated that the action may be reversed and the block dropped to printing position at a predetermined travel of the carriage thereunder, instead of the head being raised into contact with the block.

I claim:

1. In a block printing machine, a printing block and a color carriage having at least two color applying units extending longitudinally thereof, both of which are simultaneously operable for applying different colors to different longitudinal portions of the block, the color carriage having paint troughs adapted to substantially continuously supply the color applying units.

2. In a block printing machine, a color carriage having two rollers extending across the length thereof, each of which is in a separate trough, and means for simultaneously effecting a raising or lowering movement of both rollers.

3. The method of printing floor coverings in a block printing machine which consists in moving a color carriage which is divided longitudinally and transversely to a plurality of separate color applying units beneath a printing block and causing the printing block to receive paint from the color units during a portion only of the time which the carriage is moving beneath the block.

4. In a block printing machine, a printing block, a plurality of paint rolls movable thereunder, means for controlling the relative vertical movement between the paint rolls and the block, whereby paint is applied simultaneously by said paint rolls to selected different portions of the printing block, and means for continuously supplying paint to the paint rolls.

5. In a block printing machine, a printing block, a plurality of paint rolls movable thereunder, means for controlling the relative vertical movement between the paint rolls and the block, whereby paint is applied simultaneously by said paint rolls to selected different portions of the printing block, and color troughs movable with the paint rolls and adapted to continuously supply paint to the paint rolls.

6. In a block printing machine, a printing block, a plurality of paint rolls movable

thereunder, means for controlling the relative vertical movement between the paint rolls and the block, whereby paint is applied simultaneously by said paint rolls to selected 5 different portions of the printing block, and color troughs movable with the paint rolls and adapted to continuously supply paint to the paint rolls, the paint rolls having doctor blades for determining the amount of paint 10 which they apply to the printing block.

7. In a block printing machine, a printing block, a color carriage having a paint box and reciprocable back and forth beneath the block, a paint-applying roller on the carriage, a doctor blade cooperating with the roller, and means controlling movement of the roll into and out of position to engage and apply paint to a block, said means being effective for holding the roll in paint-applying 20 position during a portion only of its travel beneath the block, the doctor blade being movable with the roller.

8. In a block printing machine, a printing block, a color carriage including a paint box 25 reciprocable back and forth beneath the block, a paint-applying roller on the carriage, said roller being substantially in fixed position relative to the paint box, and means for bodily raising the paint box and maintaining the same in elevated paint-applying 30 position during a portion only of its travel beneath the block.

In testimony whereof I have hereunto set
my hand.

35 ROBERT A. BALDERSON.
